UNITED STATES PATENT OFFICE.

EDSON C. COVERT, OF CHICAGO, ILLINOIS, ASSIGNOR TO AMERICAN STEEL FOUNDRIES, OF NEW YORK, N. Y., A CORPORATION OF NEW JERSEY.

CLAMP FOR FLASKS.

1,027,695.

Specification of Letters Patent.

Patented May 28, 1912.

Application filed September 11, 1911. Serial No. 648,789.

To all whom it may concern:

Be it known that I, EDSON C. COVERT, a citizen of the United States, residing at Chicago, in the county of Cook and State 5 of Illinois, have invented certain new and useful Improvements in Clamps for Flasks, of which the following is a specification.

My invention relates to clamps and has reference to a novel, quick-acting, pneumatic 10 clamp for use on flasks.

In the art of molding, particularly in connection with the use of molding machines, clamps are necessary for holding the flask and drag or cope in place while the jarring 15 or tamping action is secured. In order to secure the best results these clamps should be so constructed that they may be applied or removed quickly and hold the parts securely together. I have therefore designed 20 and show in the accompanying drawings a form of clamp adapted for use on the pattern plate of a molding machine, this clamp being actuated by fluid pressure and being self-adjustable to variations in the 25 articles to be clamped.

My invention will be more readily understood by reference to the accompanying drawings, wherein,

Figure 1 is a section through a pattern 30 plate and flask, my novel clamp being shown in elevation; Fig. 2 is a bottom plan view of the pattern plate a part thereof being broken away, and Fig. 3 is an end elevation of the clamp, flask and plate.

Referring more particularly to the drawings, it will be seen that to a plate 10, having downwardly projecting flanges 11, 12, I attach by means of suitable bolts, a cylinder 13. This cylinder is connected at 14 to a 40 suitable source of fluid pressure, not shown. Within the cylinder is seated a piston 15, connected to a piston rod 16. To the end of the rod 16 is connected a bifurcated member 17, the two legs of the member 17 passing 45 through openings provided therefor in the depending flange 12. Near the outer ends of the member 17 and extending downwardly is provided a recess 18, having a vertical wall on one side and on the other side 50 an inclined approach 19. A flange 10^a, projecting from the plate 10, provides a bearing within which a pin 20 is seated. A clamping jaw 21 is mounted for oscillation on the pin 20, the pin passing through a slotted 55 opening 22, in the body portion of the jaw.

By means of the slot, the clamping jaw is permitted a limited bodily movement in line with the slot. The lower end of the jaw 21 is provided with an opening through which a pin 23 is inserted, this pin 23 being preferably of substantially the same size as the opening 18. A flask 24 is shown seated on the pattern plate, this flask being provided with a flange 25 with which the jaw member 21 coöperates.

As shown in Fig. 2, I prefer to provide two clamps to each pattern plate, these clamps being mounted on the diagonal corners. Inasmuch as the other clamps are duplicates of the one just described, a further description will not be made.

The operation of the device is as follows: A flask is placed on the base, the jaw of the clamp being then in the dotted line position of Fig. 1. Fluid under pressure is admitted to the rear of the piston 15, thus causing its advance and the advance of the member 17, within the recess 18 of which the pin 23 is seated. This will cause the jaw member to rotate about the pin 20 and bring the 80 jaw of the member 21 into contact with the flange 25 of the flask. Further advance of the piston and the member 17 will cause the unseating of the pin 23 from the recess 18, and tend to shift or wedge the jaw member 85 downward because of the incline 19, this shifting being permitted by the slot 22. It will be seen that by this means an extremely strong gripping action is secured and that the holding power will be maintained easily 90 and without maintaining the full fluid pressure necessary to secure the gripping action.

I claim:

1. A clamp comprising, in combination, a support, a clamp member rotatably and slidably connected to said support, a reciprocating member arranged to act upon said clamping member, and fluid pressure means for actuating said reciprocating member, substantially as described.

2. A clamp comprising, in combination, a base, a clamping jaw rotatably and slidably connected to said base, a reciprocating member arranged to cause rotation of said clamping jaw when shifted in one direction and rotation and wedging when shifted in another direction, and means for actuating said reciprocating member, substantially as described.

3. A clamp comprising, in combination, a

- base having a pin, a clamping jaw provided with a slot, said pin being seated in said slot, a pin carried by said clamping jaw, a reciprocating member having a recess and 5 an inclined approach to said recess, the pin on said clamping jaw coöperating with said recess and said inclined approach, and means for actuating said reciprocating member, substantially as described.
- 10 4. A clamp comprising, in combination, a support, a slotted lever having a clamping jaw associated with said support, a recipro-

cating member, and means associated with said reciprocating member and said lever and so arranged that on the motion of said reciprocating member in one direction said lever is simultaneously rotated and wedged downward, and means for shifting said reciprocating member, substantially as described. 15
